UNITED STATES PATENT OFFICE.

GEORGE M. WALTER, OF PHILADELPHIA, PENNSYLVANIA.

DESIGN FOR A MEASURE.

SPECIFICATION forming part of Design No. 30,051, dated January 24, 1899.

Application filed December 28, 1898. Serial No. 700,566. Term of patent 7 years.

To all whom it may concern:

Be it known that I, GEORGE M. WALTER, a citizen of the United States, residing in the city and county of Philadelphia, State of Pennsylvania, have invented and produced a new and original Design for a Measure, of which the following is a specification, reference being had to the accompanying drawings, forming part thereof.

10 The leading feature of my design for a measure is a body formed of measuring-chambers of different capacities, one entering the other and opening in opposite directions.

Figure 1 represents a perspective view of 15 a measure embodying my invention. Fig. 2 represents a section thereof on line xx , Fig. 1.

In the drawings, A designates the body of the measure, the same consisting of the measuring-chambers B and C, one entering the other, they being of different capacities, independent of each other by the base between them, and opening in opposite directions. 20

D designates a handle attached to the body.

Having thus described my invention, what I claim as new, and desire to secure by Letters 25 Patent, is—

The design for a measure substantially as shown and described.

GEORGE M. WALTER.
